(Cl. D71—1)

Fig. 1.

Fig. 2.

To all whom it may concern:

Be it known that I, Sidney Mitchell, a British subject, residing at Godalming, in the county of Surrey, England, have invented a new, original, and ornamental Design for a Life Raft, of which the following is a specification, reference being had to the accompanying drawing, forming part thereof.

Figure 1 is a top plan of a life raft, showing my new design with the cover in its normal unoccupied position, and

Figure 2 is a side perspective view of the same with the cover in its occupied position.

I claim:

The ornamental design for a life raft, as shown.
